LOCOMOTIVE BOILER STRUCTURE

John A. Pilcher, Roanoke, Va.

Application October 18, 1930. Serial No. 489,660

24 Claims. (Cl. 122—493)

My invention relates to the construction of boilers of the type in which boiler sheets form a corner where the steam pressure tends to distort the sheets from the desired form. A familiar example of such structure is found in railway steam locomotive boilers where the roof sheet meets the back head and where the wrapper sheet meets the front tube sheet. I shall use the term head as indicating either of these sheets. It is customary to provide braces extending diagonally across the corners and connecting the roof sheet and the vertical heads. These braces are in addition to the staybolts connecting the crown sheet and roof sheet and the staybolts connecting the back head and firebox back sheet.

The general object of my invention is to provide a form sustaining boiler head and to reduce the weight and cost of the usual construction referred to and to reduce the cost of maintenance which results from the necessity of frequent inspection and tightening of securing elements relied upon to maintain the shape of the associated parts of the boiler. I attain this object by making a substantial part of the head with integral reinforcing webs and flanges, and preferably by embodying the desired structure in a one piece casting which is rigid enough to maintain its form against any pressure present in boiler operation.

Other detail objects of my invention will be apparent from the following description taken in connection with the accompanying drawing forming a part of my specification in which—

Figure 1 is a longitudinal vertical section through the upper rear corner of a locomotive firebox showing the adjacent crown and roof sheets, door sheet, and back head.

Figure 2 is a rear elevation of a longitudinal half of the structure shown in Figure 1.

Figure 3 is a vertical transverse section taken on the line 3—3 of Figure 1.

Figure 4 is a top view of the back head casting.

Figure 5 is a horizontal section through the back head casting taken on line 5—5 of Figure 1.

Figure 6 is a vertical longitudinal section through the upper front portion of the boiler showing the roof sheet and the casting forming the upper portion of the boiler front tube sheet.

Figure 7 is a front elevation of the structure shown in Figure 6.

Figure 8 is a horizontal section through the back wall casting and is taken on the line 8—8 of Figure 6.

Figure 9 is a top view of the casting shown in Figures 7 and 8.

The boiler roof or wrapper sheet 1, crown sheet 2, fire box door sheet 3, and back head sheet 4 are of the usual boiler plate construction except that the sheet 4 terminates adjacent the level of the crown sheet and the upper portion of the back head comprises a casting including a body wall member 5 having a flange 6 extending along the top and ends of wall 5 for attachment of the roof sheet. A horizontal web 7 extends from side to side of the boiler and merges with wall 5 and each of its ends is forked to provide upwardly and downwardly inclined arms 8 and 9, each of which has a similarly inclined flange 10 for attachment to the roof sheet. Flanges 10 merge with and form, in effect, extensions of flange 6. Web 7 and arms 9 are provided with suitable openings for the extension therethrough of the usual staybolts 11 which connect the roof sheet and crown sheet.

Wall 5 is further reinforced, and flange 6 and web 7 are also braced, by a plurality of upright webs 12, preferably extending the full depth of wall 5 and with their forward edges terminating short of the staybolts 11, although, if desired, these webs 12 may be projected between the staybolts and made of any desired depth.

Web 7 is further reinforced by an upright flange 13 extending along its forward edge and merging with the upper arms 8 at the ends of the web 7. Suitable ribs 14 extend vertically between web 7 and flange 13.

Suitable bosses 15, 16, 17, and 18 are provided on wall 5 for mounting the throttle valve stem, 90 throttle lever, water gage column, and washout plugs. Similar bosses may be provided for other equipment which it is desired to apply to the wall member.

I prefer to add a series of pads 19 to the outer face of the wall 5 for the purpose of indicating the location of webs 7 and 12 whereby workmen will be guided in drilling through the wall for attaching bolts, rivets, etc. This structure allows for the ready reinforcing of the back head member 5 wherever any openings are necessary or any fittings and connections are placed on the member.

The back head sheets 4 are shown welded to the lower edge of the member 5 as indicated at *n* and the roof sheets are shown riveted to the member 5 as indicated at *m*. But it is to be understood that riveted or welded joints may be provided between the cast member 5 and any or all of the sheets.

The casting forms a beam of great strength, extending from side to side of the boiler and capable of taking care of any load that may come against wall 5 from internal pressure. The bifurcated ends provide for rivets to the roof sheet which will adequately resist the forces concentrated at the ends of the beam and also will withstand the full load which may be applied to the top portion of the member 5. The arms at the 10 end of the beam accommodate the ends of one row of staybolts between them and the inclination of the lower arm 9 disposes it more nearly normal to the staybolts and minimizes the size of the staybolt openings therethrough. By providing flange 13 entirely on the upper face of web 7, I avoid any tendency to trap steam rising from the crown of the fire box below web 7.

The principle of the design of the back head is followed in constructing the front head member of the boiler, illustrated in Figures 6 to 9 inclusive, in which the front flue sheet S is seated against a ring R secured to the boiler wrapper sheet and is held against distortion by the flues F inserted in openings K and expanded 25 in the usual manner. The upper portion of the head includes a wall 20 provided with an integral arcuate flange 21 for attachment to the roof sheet 1 and also includes an integral horizontal web 22 projecting outwardly below the roof sheet and 30 having a reinforcing flange 23 on its inner edge projecting above and below the web. Vertical webs 24 and 25 stiffen wall 20 and webs 25 and suitable ribs 26, and others if desired, extend to flange 23 and tie all the parts together, thus 35 forming a beam of great strength. A suitable opening 27 in wall 20, surrounded by a deep circular rib 28, provides an outlet for steam from the dry pipe 29 and the rib is enlarged as at 30 to provide for studs securing the flange on the 40 steam pipe which leads to the steam chest or to the superheater header.

The flue sheet S is welded to wall member 20, as indicated at n', although it may be overlapped and riveted thereto if desired.

45 This front head may be modified by carrying flange 21 all around the upper edge of the head in which case the ring R may be eliminated. The webs 7 and 22 should be of a depth at least approximating the depth of the cast upper part 50 of the head, the usual comparatively shallow ribs provided for attachment of braces being alone inadequate to replace these corner braces. These webs may, however, be varied in shape and position. Various other modifications in the details 55 of the structure may be made and one or more of the desirable features of my design may be eliminated without departing from the spirit of my invention. I consider it within the scope of my invention to form the heads out of two, or even 60 more castings welded together into an integral whole to form an integral unit adapted for the intended purposes of my one piece casting.

Irrespective of these and other modifications, 65 my invention embodies an integral structure which replaces in the usual construction a very large number of pieces including, in addition to the boiler backhead and flue sheet, T-bar brackets, rivets for attaching same, lugs on the boiler, 70 rivets for attaching the same, a large number of pieces passing from the T-bar brackets to the boiler roof sheet, lugs and pins for attaching the same and cotters for holding the pins. Due to the elimination of the usual braces between the 75 roof sheet and the backhead, the upright rein-

forcing webs can be freely arranged to best resist the forces applied to the backhead.

Careful calculations comparing these two structures have demonstrated a very large reduction in weight and a very large reduction in cost. 80

Having described my device as above what I claim is:

1. A locomotive boiler head structure comprising a wall member extending across the boiler and a deep web integral therewith and disposed transversely thereof from end to end, there being a flange along the outer edge of said web spaced from said member, whereby said structure forms a flanged beam extending from side to side of the boiler. 85

2. A locomotive boiler head structure comprising a wall member and an integral deep web disposed perpendicularly thereof, there being a flange along the outer edge of said web, and elements disposed transversely of said web between the same and said wall member and said flange for distributing the forces applied to the structure, said wall member having its edge turned inwardly and merging with the ends of said web and flange and arranged for attachment to the 100 boiler side and top sheets. 90

3. A locomotive boiler head structure consisting of a wall member, integral arms extending transversely of said wall member from the edge thereof for attaching a boiler roof sheet and rib-like elements arranged perpendicular to said member and reinforcing the same to constitute therewith a beam between said arms and arranged to withstand high steam pressures applied thereto, irrespective of braces to the boiler roof 110 sheet. 105

4. A locomotive boiler head casting comprising a vertical wall member, and a horizontal web reinforcing said wall member with its ends forked and terminating in flanged arms for attaching 115 the boiler roof sheet.

5. A locomotive boiler head casting comprising an upright wall member, and a horizontal web reinforcing said wall member with each end forked to form roof sheet attaching arms inclined upwardly and downwardly respectively from the plane of said web. 120

6. A locomotive boiler head casting comprising a wall member having an inwardly disposed flange along its edge for securing a roof sheet thereto, a reinforcing web spaced from its edge, and a roof sheet attaching arm at the end of said web. 125

7. A locomotive boiler head casting comprising a main wall member having an inwardly disposed flange along its edge for securing a roof sheet thereto, and having a relatively deep reinforcing web extending transversely of said wall member and said flange, and roof sheet attaching arms extending from said wall member and merging with the ends of said web and projecting beyond 135 the same for securing the casting to a roof sheet.

8. A locomotive boiler head casting comprising a wall member having an inwardly disposed flange along its edge for securing a roof sheet thereto, a reinforcing web spaced from its edge, and a plurality of roof sheet attaching arms at each end of said web and merging with said flange. 140

9. In a locomotive boiler, a firebox crown sheet, a roof sheet, a firebox rear sheet, a back head member above said rear sheet and secured to said roof sheet, vertical reinforcing webs on said back head extending from above the level of said crown sheet to said roof sheet, and a horizontal web on 145 150

- said back head intermediate said crown sheet and roof sheet and merging with said vertical webs, staybolts connecting said crown sheet and roof sheet, and staybolts connecting said rear sheet and back head, the boiler being free of braces between said roof sheet and back head. 80
10. In a locomotive boiler, a firebox crown sheet, a roof sheet, a back head casting including a horizontal reinforcing web projecting between said crown sheet and roof sheet and having each end forked to form roof sheet attaching arms inclined upwardly and downwardly respectively, and staybolts connecting said crown sheet and roof sheet and extending through suitable openings provided in said web and at least one of said arms. 85
11. In a locomotive boiler, a roof sheet, fire box rear and crown sheets, and a back head, the lower portion of which is held against distortion by means of staybolts to said rear sheet and terminates near said crown sheet and the upper portion of which above the fire box crown sheet comprises a wall member and an integral element disposed transversely thereof and extending from side to side of the boiler to reinforce said wall member against distortion, said wall member and element being secured directly to said roof sheet. 90
12. In a locomotive boiler, a roof sheet, fire box rear and crown sheets, and a back head, the lower portion of which consists of boiler plate and is held against distortion by means of staybolts to said rear sheet, and the upper portion of which is a casting formed separately and includes a wall member secured to said lower portion and an element integral with and disposed transversely of said wall member and extending from side to side of the boiler and secured directly to said roof sheet to reinforce said wall member against distortion. 100
13. In a locomotive boiler, a roof sheet, a fire box crown sheet, a back head, the lower portion of which is held against distortion by means of staybolts and the upper portion of which above the fire box crown sheet comprises a wall member with an attaching flange along its edge, and a plurality of transversely disposed webs integral therewith and extending in different directions across the same and merging with said flange to reinforce the wall member against distortion intermediate its edges. 115
14. In a locomotive boiler, a back head, the lower portion of which is held against distortion by means of staybolts and the upper portion of which above the fire box crown sheet comprises a wall member with its edge portion turned inwardly for direct attachment to a boiler roof sheet, and integral arms comprising restricted extensions of said wall member for direct attachment of a boiler roof sheet. 125
15. In a locomotive boiler, a back head, the lower portion of which is held against distortion by means of staybolts and the upper portion of which above the fire box crown sheet comprises a wall member having an inwardly disposed flange along its edge for securing the boiler roof sheet and having an integral reinforcing web spaced from its edge and extending across the boiler and an elongated arm projecting from the end of said web for direct attachment to the boiler roof sheet. 135
16. In a locomotive boiler, a back head, the lower portion of which comprises a sheet held against distortion by means of staybolts connected to said sheet and the fire box door sheet and the upper portion of which above the fire box crown sheet comprises a wall member having an inwardly extending flange around its top edge for di- 140
- rectly securing a roof sheet thereto, and transverse beam like members integral with said wall member and flange and extending across the boiler for reinforcing said wall member and flange against distortion. 145
17. In a locomotive boiler having a section substantially filled with flues, and a section above the same for dry steam, a wrapper sheet, a front head, the lower portion of which comprises a flue sheet held against distortion by the boiler flues, and the upper portion of which head above the flues comprises a wall member and an element integral therewith projecting transversely therefrom and extending from side to side of the boiler to reinforce said wall member against distortion, there being a direct connection between the ends of said element and said wrapper sheet. 150
18. In a locomotive boiler, a front head, the lower portion of which consists of boiler plate and is held against distortion by the boiler flues, and the upper portion of which is a separately formed casting and includes a wall member secured to said lower portion, and a web integral with said wall member and extending transversely thereof from side to side of the boiler, and additional webs disposed transversely of said first mentioned web, said webs being arranged to reinforce said wall member against distortion and to provide direct connection between said casting and the wrapper sheet. 160
19. In a locomotive boiler, a front head, the lower portion of which consists of boiler plate and is held against distortion by the boiler flues, and the upper portion of which is a separately formed casting and includes a wall member secured to said lower portion and having a web integral therewith and disposed transversely thereof, there being a flange along the outer edge of said web, and elements disposed transversely of said web between the same and said wall member and said flange for distributing the forces applied to the structure, there being a direct connection between the ends of said web and said wrapper sheet. 170
20. In a locomotive boiler, a front head, the lower portion of which consists of boiler plate and is held against distortion by the boiler flues, and the upper portion of which is formed separately and includes a wall member secured to said lower portion and having a deep circular rib integral therewith, to which the boiler dry steam pipe is attached and having a still deeper horizontal web adjacent to said circular rib and extending across said wall member and merging at its ends with flanges for direct attachment to the wrapper sheet. 180
21. In a locomotive boiler, a roof sheet, a crown sheet, a front head, comprising a boiler plate portion with its upper edge terminating adjacent to the level of said crown sheet, and a cast member secured to and extending upwardly from said upper edge and directly connected to said roof sheet, and provided with a reinforcing web extending a substantial distance over said crown sheet and from side to side of said roof sheet with its ends connected directly thereto. 190
22. A locomotive boiler head casting comprising a vertical wall member, and a horizontal web reinforcing said wall member with its ends formed for attaching the boiler roof sheet. 195
23. In a locomotive boiler, an integral cast metal structure including a wall constituting the upper part of a boiler head from side to side of the boiler, a web extending perpendicularly of said wall, said web in greatest depth at least approxi- 200

mating the depth of said wall, and bracing ribs extending across the corner between said wall and said web, said web and ribs forming with said wall a beam of sufficient strength to resist 5 the boiler pressure without the use of additional braces to said wall, said structure being arranged at its edges for attachment to the boiler wrapper sheet.

24. In a locomotive boiler, a roof sheet, a fire box crown sheet, and an integral cast metal structure including a wall constituting the upper part

of the boiler head extending from side to side of the boiler and substantially between the levels of said roof and crown sheets and a web extending at an angle to said wall and at least approximating in depth the distance between said roof and crown sheets, said web forming with said wall a transverse beam of sufficient strength to resist boiler pressures without the use of additional braces to said wall.
